(57) **CLAIM**

The ornamental design for a dual-monitor computer, as shown and described.

DESCRIPTION

FIG. 1 is a perspective view of a dual-monitor computer, in accordance with a first embodiment;

FIG. 2 is a front view of the dual-monitor computer in FIG. 1, in accordance with the first embodiment;

FIG. 3 is a back view of the dual-monitor computer in FIG. 1, in accordance with the first embodiment;

FIG. 4 is a right side elevation view of the dual-monitor computer in FIG. 1, in accordance with the first embodiment;

FIG. 5 is a left side elevation view of the dual-monitor computer in FIG. 1, in accordance with the first embodiment;

FIG. 6 is a top plan view of the dual-monitor computer in FIG. 1, in accordance with the first embodiment;

FIG. 7 is a bottom plan view of the dual-monitor computer in FIG. 1, in accordance with the first embodiment;

FIG. 8 is a perspective view of a dual-monitor computer, in accordance with a second embodiment;

FIG. 9 is a front view of the dual-monitor computer in FIG. 8, in accordance with the second embodiment;

FIG. 10 is a back view of the dual-monitor computer in FIG. 8, in accordance with the second embodiment;

FIG. 11 is a right side elevation view of the dual-monitor computer in FIG. 8, in accordance with the second embodiment;

FIG. 12 is a left side elevation view of the dual-monitor computer in FIG. 8, in accordance with the second embodiment;

FIG. 13 is a top plan view of the dual-monitor computer in FIG. 8, in accordance with the second embodiment;

FIG. 14 is a bottom plan view of the dual-monitor computer in FIG. 8, in accordance with the second embodiment;

FIG. 15 is a perspective view of a dual-monitor computer, in accordance with a third embodiment;

(Continued)

FIG. 16 is a front view of the dual-monitor computer in FIG. 15, in accordance with the third embodiment; FIG. 17 is a back view of the dual-monitor computer in FIG. 15, in accordance with the third embodiment; FIG. 18 is a right side elevation view of the dual-monitor computer in FIG. 15, in accordance with the third embodiment; FIG. 19 is a left side elevation view of the dual-monitor computer in FIG. 15, in accordance with the third embodiment; FIG. 20 is a top plan view of the dual-monitor computer in FIG. 15, in accordance with the third embodiment; FIG. 21 is a bottom plan view of the dual-monitor computer in FIG. 15, in accordance with the third embodiment; FIG. 22 is a perspective view of a dual-monitor computer, in accordance with a fourth embodiment; FIG. 23 is a front view of the dual-monitor computer in FIG. 22, in accordance with the fourth embodiment; FIG. 24 is a back view of the dual-monitor computer in FIG. 22, in accordance with the fourth embodiment; FIG. 25 is a right side elevation view of the dual-monitor computer in FIG. 22, in accordance with the fourth embodiment; FIG. 26 is a left side elevation view of the dual-monitor computer in FIG. 22, in accordance with the fourth embodiment; FIG. 27 is a top plan view of the dual-monitor computer in FIG. 22, in accordance with the fourth embodiment; FIG. 28 is a bottom plan view of the dual-monitor computer in FIG. 22, in accordance with the fourth embodiment; FIG. 29 is a perspective view of a dual-monitor computer, in accordance with a fifth embodiment; FIG. 30 is a front view of the dual-monitor computer in FIG. 29, in accordance with the fifth embodiment; FIG. 31 is a back view of the dual-monitor computer in FIG. 29, in accordance with the fifth embodiment; FIG. 32 is a right side elevation view of the dual-monitor computer in FIG. 29, in accordance with the fifth embodiment; FIG. 33 is a left side elevation view of the dual-monitor computer in FIG. 29, in accordance with the fifth embodiment; FIG. 34 is a top plan view of the dual-monitor computer in FIG. 29, in accordance with the fifth embodiment; and, FIG. 35 is a bottom plan view of the dual-monitor computer in FIG. 29, in accordance with the fifth embodiment. The claimed dual-monitor is not limited to the scale shown herein. The broken lines are directed to environment and form no part of the claimed design. The surface shading lines illustrated in the drawings are provided only to indicate the contour or lack of curvature. The shading lines do not indicate color, texture, or markings that actually exist

thereon, or indicia, graphic representations, surface treatment, or any other ornamentation applied to the article.
